UNITED STATES PATENT OFFICE

GEORG NÄGELE, OF ITTLINGEN, GERMANY

APPARATUS FOR AGITATING THE AIR

Application filed September 19, 1928, Serial No. 307,000, and in Germany September 19, 1927.

My invention relates to improvements in apparatus for agitating the air, and more particularly in apparatus adapted to be worn by the person at parties and balls. The object of the improvements is to provide an apparatus of this type which can conveniently carried by the person, and which is adapted to be fixed to the arm so that it is not lost by negligence. With this object in view my invention consists in constructing a mechanically operated fan of small dimension and provided with means for attaching the same to the arm of the person. For operating the fan mechanism such as a clock work is provided which is able to supply the necessary power for a long period of time without being rewound. For agitating the air a fan of the rotary vane type may be provided. But I prefer to provide a fan of a form which is pleasant to the eye, for example by constructing the operating member in a form representing a dancing girl or in the form of the wings of a butterfly or the like. My improved agitating apparatus will particularly be used when dancing, and therefore I prefer to provide the same with a spray for spreading perfumes, the said spray being preferably operated by the mechanism for operating the fan. In the preferred construction of the spray means are provided for throwing the same into and out of operation at will.

For the purpose of explaining the invention several examples embodying the same have been shown in the accompanying drawings in which the same reference characters have been used in all the views to indicate corresponding parts. In said drawings,

Fig. 1 is a sectional elevation showing the fan,

Fig. 2 is a sectional plan view taken on the line II—II of Fig. 1,

Fig. 3 is a sectional elevation showing a modification, and

Fig. 4 is a sectional plan view taken on the line IV—IV of Fig. 3.

In the example shown in Fig. 1 the fan comprises a figure α representing a dancing girl, the said figure being carried by a spindle b disposed axially of a box f . To the

said spindle a pinion e is secured which is located within the casing, and which is in mesh with a gear wheel g connected with a pinion h . The pinion h is in mesh with a gear wheel i connected with a suitable motor such as a spring-actuated clock work k , suitable means being provided for rewinding the said work. The clock work may be thrown into and out of operation by means of a button l projecting through the wall of the casing f . Means for rewinding the clock and for throwing the same into and out of operation by means of the button l are known in the art, and therefore I deem it not necessary to describe the same more in detail. The gearing i, h, g, e is such that the figure α is rapidly rotated.

As shown the figure is made in two parts connected with each other by a hinge m . Thus a comparatively large figure may be provided for agitating the air, though the said figure does not require much room when out of use. Preferably the figure is rockingly mounted on the spindle b by means of a pivot bolt n , so that it may be rocked downwardly when out of use. Thus, injury to the figure is prevented. The casing f is not larger than the casing of a watch carried by the arm of the person, so that the apparatus does not hinder the person and has a tasteful appearance.

In the modification shown in Figs. 3 and 4 the agitating apparatus is in the form of the wings o of a butterfly, the said wings being rockingly mounted at p and having arms r extending into the casing q . The wings are acted upon by springs w , tending to bend the same downwardly, and for operating the same a disk t is rotatably mounted within the casing q , which disk is provided circumferentially with wedge-shaped cams s adapted to engage the wings between the arms r and to rock the same upwardly and into the position shown in Fig. 3. The disk is rotated from the spring motor k through the intermediary of gear wheels v and u . Whenever upon rotation of the disk the cams s pass between the arms r , the wings o are removed upwardly, and thereafter they are thrown downwardly by the springs w .

Between the top wall of the casing *q* and one of the arms *r* there is a rubber ball *x* connected with a spray *y* for spreading perfume, the said spray opening through a nozzle *z* into the outer air. Thus, whenever the arm *r* is rocked upwardly by one of the cams *s* the ball is compressed thus spraying the perfume, and after the cam has passed the ball is expanded by its elasticity. The ball is connected with a slide 2 having an arm extending through a slot made in the top wall of the casing *q*, so that the ball may be shifted outwardly and out of position for engagement by the arm *r*. Also in this case I prefer to construct the wings *o* so that they are adapted to be rocked downwardly and on the box *q*, so that they are not injured when out of use.

In both cases means are provided for attaching the apparatus to the arm of the lady. By way of example a belt 3 is attached to the casing.

I claim:

An apparatus for agitating air comprising a box, a pair of agitating members in the form of wings hingedly mounted on said box, arms projecting from said wings into the box, means adapted to hold the wings flat on top of the box, a mechanically operated revolving disk provided with a wedge-shaped cam member adapted for intermittent engagement between said arms to push them apart, thereby raising said wings from the flat position in opposition to said folding means.

In testimony whereof I hereunto affix my signature.

GEORG NÄGELE.
